[57] CLAIM

The ornamental design for a face, neck and chin exerciser, as shown and described.

DESCRIPTION

FIG. 1 is a perspective view of the face, neck and chin exerciser located in a user's mouth, the broken lines showing environment only and forming no part of the claimed design; FIG. 2 is a front elevational view thereof; FIG. 3 is a rear elevational view thereof; FIG. 4 is a right side elevational view thereof, the left side elevational view being a mirror image thereof; FIG. 5 is a top plan view thereof, the bottom plan view being a mirror image thereof; FIG. 6 is a perspective view of the face, neck and chin exerciser in a flat position; FIG. 7 is a front elevational view thereof; FIG. 8 is a top plan view thereof, the bottom plan view being a mirror image thereof; FIG. 9 is a rear elevational view thereof; and, FIG. 10 is a right side elevational view thereof, the left side elevational view being a mirror image thereof.
